UNITED STATES PATENT OFFICE

2,581,181

HEAVY-DUTY AIR CIRCUIT BREAKER

John A. Favre, Drexel, Pa., assignor to General Electric Company, a corporation of New York

Application January 7, 1950, Serial No. 137,411

14 Claims. (CL 200—153)

1

The invention relates to circuit breakers, particularly air circuit breakers, and the principal object is to provide an improved separately articulated compound sequential toggle actuated arcing and main contact form of heavy-duty air circuit breaker capable of closing on exceptionally large momentary load currents and having a current-interrupting capacity of the same magnitude, for example, one hundred thousand amperes.

With such large momentary currents carried during the closing and opening of the arcing and main contacts of the breaker, severe sparking and "blow-offs" of a destructive and explosive character are likely to occur unless sufficient wiping pressure as well as successive actuation of these contacts are very accurately produced in properly timed sequence. Thus insufficient arcing contact wiping pressure at the instant the main contacts engage or disengage may result in the relatively large current becoming highly concentrated in one or more minute conductive paths between the main contacts, thereby producing such a high concentration of the electrical energy that immediate volatilization of the main contact material occurs with explosive "blow-off" force. Similar results are likely to occur in case of an untimely or premature decrease in the main contact wiping pressure before the actual separation thereof occurs or in case the separating speed thereof is insufficient to prevent "restrike" upon a rapid sequential separation of the arcing contacts.

Hence, a particular object is to provide an improved positive sequential timing form of separately articulated heavy-duty arcing and main contact compound toggle wiping and actuating linkage capable of establishing and maintaining the required values of wiping pressure therebetween in proper relation with their sequential closing and opening at the critical times necessary to overcome the severe sparking and destructive "blow-offs" to which these contacts ordinarily are subjected in such heavy-duty service.

Another object is to provide an improved compound sequential toggle wiping and actuating linkage for the separately articulated contacts that will substantially counterbalance or neutralize the heavy electrodynamic forces of the arcing and main contact loops so as to reduce the reaction thereof on the closing mechanism when the breaker is closed on a heavy fault. This materially facilitates a successful closing operation against the normal contact wiping spring forces by means of a stored energy device or other operator having a limited maximum closing power.

2

A further object is to utilize the heavy electrodynamic forces of the main and arcing contact current loops for quickly accelerating the joint wiping movement of the separately articulated main current-carrying contacts as well as for maintaining the required contact pressure therebetween until the actual separation thereof occurs before the arcing contact pressure sequentially decreases and thereby secure as much speed and contact pressure as possible in the opening of the breaker under heavy overloads to minimize sparking and "blowoffs" and reduce the possibilities of "restriking" in interrupting currents of large magnitude.

Another object is to provide an improved compound sequential toggle linkage operable in closing the breaker to quickly effect wiping joint movement of the separately articulated arcing contacts against normal spring pressure and maintain substantially uniform the normal spring pressure therebetween both during the sequential closing wiping engagement of the main current-carrying contacts against normal spring pressure as well as during the reverse joint wiping movement of the main contacts until after the accelerated separation thereof occurs in the opening of the breaker. In this way separate and successive wiping engagement and disengagement of the arcing and main contacts is positively obtained in reverse sequence.

Another object is to provide an improved double latch type of trip-free power-amplifying circuit breaker operating toggle mechanism having a latched-in centrally fulcrumed closing toggle lever biased open and provided with a releasable fulcrum lever having a separate latch controlled by a sensitive overload current-responsive means so as to operate in conjunction with the heavy electrodynamic force of both the main and arcing contact electrodynamic loops to effect the rapid opening of the breaker.

Further objects and advantages of the invention will appear in the following description of the accompanying drawing in which Fig. 1 shows the improved separately articulated arcing and main contact structure of the heavy-duty circuit breaker in the closed position provided with the improved compound sequential toggle wiping and actuating linkage of the present invention and Fig. 2 shows the relative positions of the parts in the open position of the circuit breaker.

As shown, the circuit breaker indicated generally by the reference character 9 is provided with an upper suitably insulated current-conducting terminal stud 10 having a main contact 11

directly pivoted thereon by means of the conducting pivot pin 12 resting in the conducting bearing notch 13. The separately articulated arcing contact 15 also is directly pivoted on stud 16 by means of the conducting pin 16 resting in the conducting bearing notch 17. Both pivot pins 12 and 16 are held in current-conducting relation with their respective bearing notches by means of the holding bar 20 that is secured to the conductor stud 10 by screw 21. The articulated main contact 11 is provided with a wiping biasing spring 23 for biasing the main contact 11 in one direction to the position wherein stop 24 engages with an insulating shoulder 25. Similarly the arcing contact 15 is provided with a wiping biasing spring 27 operating on the pin 28 to bias in the same direction the tail 29 of contact 15 into engagement with the insulating stop 30. If desired, suitable flexible braid 31 may be provided for avoiding pitting of the main contact-bearing pin 12 during heavy faults and a similar flexible braid 32 may be provided for the arcing contact bearing pin 16 for the same purpose.

The circuit breaker 9 likewise is provided with a second suitably insulated current-conducting terminal stud 33 that is electrically connected to one end of the single turn magnetizing coil 34 for the overload tripping device 35 which may be of any usual type. The other end of coil 34 is connected to the current conductor 36 on which is pivotally mounted the second separately articulated main contact 37 by means of the conducting pivot pin 38 which is held in conducting engagement with the bearing notch 39 by means of a conducting bar 40 that is secured to the conductor 36 by means of the screw 41. In this way the two main contacts 11 and 37 are separately articulated for joint wiping movement in abutting engagement in one direction to compress the biasing spring 23 with the facings 42 of special contact material interposed therebetween. The second separately articulated arcing contact 45 is mechanically and electrically connected directly to the main contact 37 by means of pivot pin 46 and is thus supported for joint movement with the separately articulated arcing contact 15 in abutting wiping engagement in the same direction to compress the biasing spring 27 with the facings 47 of special contact material interposed therebetween. Thus, the arcing contacts 15 and 45 are jointly movable in the same direction as the main contacts 11 and 37. Any suitable form of arc quencher or chute, not shown, may be provided for extinguishing the arc between the arcing contacts 15 and 45.

In order to accurately produce the properly timed sequential engagement and disengagement of the separately articulated pairs of arcing contacts 15 and 45 and main contacts 11 and 37 with sufficient wiping contact pressure therebetween, an improved form of compound sequential toggle linkage indicated generally by the reference character 48 is provided. This linkage 48 comprises a main tension link 50 journaled at one end on the fixed pivot pin 51 to swing the other end thereof in a direction transverse the direction of joint movement of the contacts and having a compression toggle link 52 connected to the other end thereof by means of the pin 53 with the other end of the link 52 connected to the main contact 37 by means of pin 54 so as to be moved toward and away from force amplifying alignment with the tension link 50 in closing and opening the circuit breaker. The main tension

link 50 also is provided at the other end thereof with a separate compression toggle link connection with the arcing contact 45 comprising the shorter link 55 that is connected at one end to the tension link 50 by means of the offset pin 56 and the other end to the arcing contact 45 by means of pin 57 so as to be moved in the proper sequence toward and away from force amplifying alignment with the tension link 50 in closing and opening the circuit breaker. The main tension link 50 is shown provided with an insulating crossarm 60 that may serve to interconnect the similar main tension links of other poles in a multiple breaker construction with the contacts and toggle links of each pole substantially the same as shown in the drawing.

In order to obtain a further force amplifying toggle action in closing the breaker 9, the other end of the main tension link 50 is connected by 20 means of the operating toggle link 61 with a bell crank closing member 62 that is journaled intermediate its ends on the pivot pin 63 carried intermediate the ends of a releasable fulcrum lever 64 that is journaled on a fixed bearing pin 65 at one end. The other end of the releasable fulcrum lever 64 is provided with a roller 66 for engagement with the rounded end of a trip prop 67. This trip prop 67 is pivoted on the fixed pin 68 and is biased by spring 69 into engagement with the stop 70 in a position wherein the thrust from the roller 66 tends to move the prop 67 against the bias of the spring 69. For holding the prop 67 in the position in which it is shown, the latch 71 is pivoted on the pin 72 so as to engage with the upper end of the prop 67 when the roller 73 carried by the latch 71 is engaged by the trip finger 74 carried on the trip shaft 75. The overload current-responsive trip mechanism 35 may be of the usual time-delay type provided with a projecting finger 76 for engaging with the adjusting screw 77 in order to move the trip finger 74 out of engagement with the roller 73 so as to trip the breaker 9 whenever a predetermined value of current flows through the coil 34 for the required time.

The circuit breaker 9 is shown closed, in Fig. 1, with the pair of main contacts 11 and 37 in abutting wiping engagement and the shunting pair of arcing contacts 15 and 45 also in abutting wiping engagement and the bell crank operating lever 62 is held in its closing position by the engagement of the latch 80 with the pin 81 carried adjacent the free end of the bell crank lever 62. The latch 80 is pivoted on the fixed pin 82 and is biased into engagement with the pin 81 by the biasing spring 83. Suitable opening biasing springs 85 are connected between the pivot pin 53 on the main tension link 50 and a fixed supporting member 86 so as to exert a strong bias tending to rotate the main tension link 50 about its fixed pivotal supporting pin 51 and bodily move the bell crank 62 and the releasable fulcrum lever 64 about the fixed pivot pin 65 when the prop 67 is released from engagement with the roller 66 upon the required large current flow through the breaker required to operate the trip mechanism 35.

Upon the resulting opening of breaker 9, the fulcrum lever 64 is moved about its pivot pin 65 in the clockwise direction so as to compress the relatively light resetting spring 88 and thereby lower the pivot pin 63 sufficiently to release the pin 81 from engagement with the latch 80 thereby freeing the bell crank 62 for quick rotation under the bias of the opening springs 85. As soon

as this occurs, the relatively light biasing spring 28 is then free to automatically reset the lever 64 into its position in which it is shown and thereby carry the bell crank lever 62 into its circuit breaker opening position shown in Fig. 2 with the other parts of the circuit breaker mechanism also occupying their respective open positions in which they are shown.

In accordance with the present invention, when the circuit breaker is opened by the sequential toggle linkage 48 in the manner just described, the first contact actuation produced is the joint wiping movement of the two separately articulated main contacts 11 and 37. Due to the heavy overload current flow therethrough, a heavy electrodynamic force is exerted on each of these contacts tending to drive them to the left and this force performs two functions. First, it accelerates the joint wiping movement of the two main contacts 11 and 37 until the limit of motion of the contact 11 is reached wherein the stop 24 engages the shoulder 25. The second function performed by the magnetic force is in augmenting the force of the biasing spring 23 in maintaining abutting wiping engagement between the contact facings 42 during the joint wiping movement of the main contacts. This serves to minimize sparking and "blow-offs" by maintaining the required pressure between these main contacts until the quick separation thereof occurs as contact 11 is suddenly stopped by the engagement of pin 24 with shoulder 25.

During such accelerated joint opening wiping movement of the main contacts 11 and 37, the arcing contacts 15 and 45 are mechanically maintained substantially at rest and consequently a substantially uniform contact pressure is maintained therebetween by the biasing force of the wiping spring 27. Thus the breaker operating linkage 48 including the main tension link 50 and the separate sequential toggle links 52 and 55 insures, in conjunction with the pivotal mounting of the arcing contact 45 on the main pivotally mounted contact 11, that substantially no opening wiping movement of the arcing contacts can occur during the joint opening wiping movement of the main contacts as only a slight vertical sliding relative movement between the arcing contacts 15 and 45 is produced due to the compound sequential toggle pivot pins 56, 57, 46 and 38 being maintained in substantially the same alignment as shown until after the quick separation of the main contacts 11 and 37 is accomplished. Thus upon counterclockwise rotation of the main tension link 50 about its pivot pin 51 to open the breaker 9, the toggle link 52 rotates the main contact 37 about its pivot pin 38 to effect the accelerated joint wiping movement of the main contacts 37 and 11 until the pivotal movement of contact 11 is suddenly stopped by the engagement of stop 24 with the insulating shoulder 25 to produce sudden disengagement of the main contacts. During such accelerated joint wiping movement and sudden separation of the main contacts 11 and 37, the pivotal mounting of the arcing contact 45 on the main contact 37 by means of the conducting pin 46 and the toggle connection of the arcing contact 45 with the main tension link 50 by means of the separate toggle link 55 serves to produce only movement of the lower end of contact 45 while maintaining the upper end thereof at rest in firm wiping engagement with the arcing contact 15 until after the separation of the main contacts 11 and 37 occurs. Thereupon the compound se-

quential toggle mechanism operates to effect joint wiping movement of the contact 15 along with the contact 45 until the tail 29 of contact 15 engages with the insulating stop 30 to thereby produce sudden separation of the arcing contacts 15 and 45. Thereupon, the arcing contact 45 is rapidly carried to its fully open position in which it is shown by the dotted lines.

During the joint wiping movement of the arcing contacts 15 and 45, the electrodynamic forces on contact 15 are substantially counterbalanced or neutralized due to the reverse loop structure. Thus, the electrodynamic loop force set up by the current flow through contacts 15 and 45 is opposed by the electrodynamic loop force set up by the current flow through contact 15 and the opposite portion of the current-conducting terminal stud 10 on which the contact 15 is pivotally mounted by the current-conducting pin 16. Upon opening of the breaker 9, the releasable fulcrum lever 64 is automatically reset by spring 28 and likewise the prop 67 is automatically reset into engagement with the roller 66 by the spring 69 with the latch 71, the trip finger 74 and also the projecting finger 76 of the overload current-responsive trip mechanism 35 all returned to their initial holding position as shown in the drawing and with the other parts of the breaker in their respective positions indicated by the dotted lines.

In order to reclose the breaker, the bell crank closing member 62 must be operated to return the pin 81 into engagement with the latch 80. Although any suitable operating means may be employed for this purpose, the improved circuit breaker 9 shown in the drawing is particularly adapted for closing operation by the improved form of stored energy mechanism 79 that is more fully described and claimed in my co-pending application, Serial No. 196,075, filed November 16, 1950. As indicated in the drawing, this improved mechanism is provided with a closing arm 90 fixed on an operating shaft 91 and carrying a roller 92 for camming engagement with the free end 93 of the bell crank 62. The operating shaft 91 also has fixed thereon an actuating cam member 95 that is connected by the pivotal saddle 96 with a powerful compression spring 97 in which sufficient energy may be stored to effect the closing of the circuit breaker. The energy is imparted to the compression spring 97 by rotating the cam member 95 to the position in which it is shown by means of the roller 98 carried on the arm 99 that is fixed to a motor-driven shaft 100 provided with the improved powerful gear reduction and trip-free overrunning clutch mechanism more fully described and claimed in my above-mentioned co-pending application.

With sufficient closing energy stored in the powerful compression spring 97 as shown, all that is necessary for closure of the breaker is to effect rotation of the arm 99 from its dead-center position in which it is shown. Thereupon the powerful force of the compression spring 97 becomes effective to produce free overrunning of the arm 99 and the drive shaft 100 along with the operating shaft 91 so as to quickly rotate roller 92 into camming engagement with the upturned end 93 of the bell crank 62 to return the pin 81 into engagement with the latch 80 and thereby effect the reclosure of the circuit breaker 9. The stored energy closing mechanism thereupon returns to its initial position in which it is shown wherein sufficient energy is again stored in the

powerful compression spring 97 to effect the next reclosure of the breaker.

In case the circuit breaker 9 should be closed on a heavy fault during the operation of the stored energy closing mechanism, trip-free action is obtained due to the release of the prop 67 thereby releasing the fulcrum lever 64 and permitting the opening of the breaker to be accomplished in substantially the same way as previously described except that the upturned end 93 of the bell crank 62 will remain in engagement with roller 92 until the stored energy mechanism 78 is returned to its initial position which occurs immediately after the breaker is opened.

What I claim as new and desire to secure by Letters Patent of the United States, is:

1. A circuit breaker having in combination, a pair of separately articulated abutting main contacts jointly movable in one direction, a pair of separately articulated abutting arcing contacts jointly movable in one direction, and operating mechanism having a tension link pivotally supported at one end to swing the other end in a direction transverse the direction of joint movement of the contacts and provided at the other end with sequential compression toggle links having separate pivotal connections with one of each pair of contacts for effecting separate and successive wiping disengagement and engagement of said pairs of contacts in reverse sequence as the compression links successively move away from and toward force amplifying alignment with the tension link.

2. A circuit breaker having in combination, co-operating pairs of separately articulated abutting arcing and main contacts separately movable in wiping relation in the same direction, means normally biasing one contact of each pair for joint wiping movement with the other contact within a limited range, and operating mechanism having a tension link pivotally supported at one end to swing the other end in a direction transverse the direction of joint movement of the contacts in wiping relation and provided at the other end with sequential compression link connections with the other contacts of each pair for substantially separately operating each other contact through the wiping range of the corresponding one contact as the compression link connections move toward and away from force amplifying alignment with the tension link in closing and opening the breaker.

3. A circuit breaker having in combination, co-operating pairs of separately articulated abutting arcing and main contacts separately movable in wiping relation in the same direction, separate means normally biasing one contact of each pair for joint wiping movement with the other contact, means for pivotally mounting the other of the arcing contacts on the other of the main contacts and operating mechanism including a tension link pivotally supported at one end to swing the other end in a direction transverse the direction of joint movement of the contacts in wiping relation and having at the other end thereof separate toggle link connections with the other contacts of each pair offset for maintaining a substantially uniform wiping contact pressure between the pair of arcing contacts before, after, and during the wiping engagement of the pair of main contacts.

4. A circuit breaker having in combination a pair of spaced apart current conductors having separately movable inner and outer arcing and inner and outer main contacts articulated in

looped spaced relation therewith for electrodynamically biasing the inner main contact into engagement with the outer main contact, separate means biasing each inner contact for joint wiping movement with the outer contact through a limited range, and sequential linkage mechanism interconnecting the outer contacts for effecting substantially separate movement of the outer arcing and main contacts each way through the limited range of joint wiping movement with the corresponding inner contacts.

5. A circuit breaker having in combination, separately movable inner and outer main and inner and outer arcing contacts having pivotal mounting and conducting connections for electrodynamically biasing the inner main contact for joint movement in wiping engagement with the outer main contact and having the outer arcing contact pivotally mounted on the outer main contact, separate means normally biasing each inner contact for joint wiping movement with the outer contact, and sequential linkage mechanism including a tension link pivotally supported at one end and provided with sequential offset compression links of different lengths at the other end for interconnecting the outer contacts to maintain a predetermined substantially uniform contact pressure between the arcing contacts during the wiping engagement and disengagement of the main contacts.

6. A circuit breaker having in combination, separately movable abutting inner and outer main and inner and outer arcing contacts having pivotal mounting and conducting connections in looped spaced relation for electrodynamically biasing the inner main contact for joint movement in abutting wiping engagement with the outer contact, separate means normally biasing each inner contact for joint wiping movement with the abutting outer contact, stop means limiting the biased movement of each inner contact, and compound toggle operating means having a tension link pivotally supported at one end and provided at the other end with separate compression toggle links of different lengths connected with the outer contacts for separately holding the arcing and main contacts in wiping current-conducting engagement against the biasing forces exerted thereon and for effecting sequential disengagement of the outer contacts from the inner contacts at the limits of the biased movement thereof.

7. A circuit breaker having in combination a pair of main contacts separately pivoted for joint wiping movement in one direction, a pair of arcing contacts separately pivoted for joint wiping movement in the same direction, one of the arcing contacts being pivotally mounted on one of the main contacts, and operating mechanism having a tension link pivotally supported at one end to swing the other end thereof in a direction transverse the direction of joint wiping movement of the contacts and provided at the other end thereof with separate toggle link connections of different lengths with the one arcing contact and the one main contact offset for effecting separate and successive wiping disengagement and engagement of said pairs of contacts in reverse sequence.

8. A circuit breaker having in combination, a fixed conductor having an arcing and a main contact separately pivoted thereon in conducting relation therewith, a second fixed conductor having a second main contact pivoted thereon in conducting relation therewith for abutting wiping

engagement with the first pivoted main contact in electrodynamic looped relation with the conductors to increase the wiping pressure between the main contacts, a second arcing contact pivotally mounted on the second main contact in conducting relation therewith for abutting wiping engagement with the first arcing contact, and operating mechanism having a tension link pivotally supported at one end and provided at the other end with separate compression toggle link connections of different lengths with the second arcing and second main contacts for effecting sequential engagement and disengagement thereof with the corresponding first arcing and main contacts in reverse sequence.

9. A circuit breaker having in combination, a first movable main contact having a separately movable arcing contact, and each having biasing means for effecting separate wiping movement thereof in a limited range extending in the same direction, a second main contact pivotally mounted adjacent one end for joint wiping movement with the first main contact, a second arcing contact having one end thereof pivotally mounted intermediate the ends of the second main contact for joint wiping movement with the first arcing contact, and operating mechanism including a tension link pivotally mounted adjacent one end to swing the other end thereof in a direction transverse the direction of the limited ranges and having separate compression toggle links of different lengths offset for interconnecting the other end thereof with the second main contact and the second arcing contact to effect separate and successive wiping engagement and disengagement thereof with the corresponding first contacts in reverse sequence as the compression links successively move toward and away from force amplifying alignment with the tension link in closing and opening the circuit breaker.

10. A circuit breaker having in combination, a pair of main contacts separately pivoted in alignment for joint wiping movement in one direction, a pair of arcing contacts separately pivoted in alignment for joint wiping movement in the same direction, one of the arcing contacts being pivotally mounted on one of the main contacts, a pivotally mounted tension link having one end movable in a direction transverse the direction of joint wiping movement of the contacts and having separate compression toggle links of different lengths connected between the one end thereof and the one arcing contact and the one main contact for effecting separate and successive wiping disengagement and engagement of said pairs of contacts in reverse sequence upon predetermined reverse angular movements of the tension link in said transverse direction, and means including a toggle mechanism for effecting said predetermined reverse angular movement of the tension link in said transverse direction to close and open the breaker.

11. A circuit breaker having in combination, a centrally fulcrumed closing lever provided with a releasable fulcrum lever pivoted at one end and having overload current-responsive releasable holding means engaging the other end thereof, a contact mechanism operatively connected with one end of the operating lever to close the contacts upon movement of the closing lever from one position to another position and provided with biasing means for opening the contacts upon response of the current-responsive holding means

to release the fulcrum lever, and a latch engageable with the other end of the closing lever for holding the closing lever in said other position against the opening bias of the contact mechanism.

5 12. A circuit breaker having in combination, a centrally fulcrumed main operating lever provided with a releasable fulcrum lever pivoted at one end and having overload current-responsive releasable holding means engaging the other end thereof, a sequential arcing and main contact toggle mechanism having a toggle link connection with one end of the main operating lever to close the contacts sequentially upon movement of the main operating lever from one position to another position and provided with a biasing spring for opening the contacts sequentially upon response of the current-responsive holding means to release the fulcrum lever, and a latch engageable with the other end of the main operating lever for holding the main operating lever in said other position against the bias of the spring.

10 13. A circuit breaker having in combination, an operating bell crank provided with a releasable fulcrum lever pivoted at one end and having overload current-responsive releasable holding means engaging the other end thereof, switching means having separate toggle operated main and arcing contacts provided with a common tension link having an intermediate toggle link connection with one end of the bell crank to close the contacts upon movement of the bell crank from one position to another position and provided with biasing means for opening the contacts upon response of the current-responsive holding means to release the fulcrum lever, a latch engageable with the other end of the bell crank for holding the crank in said other position and closing mechanism having a member engageable with the other end of the bell crank to effect movement thereof from the one position to the other position.

15 14. A circuit breaker having in combination, an operating bell crank provided with a releasable fulcrum lever pivoted at one end and having overload current-responsive releasable holding means provided with a movable prop for engaging the other end thereof when the current is below a predetermined value, switching means having sequential toggle operating main and arcing contacts operatively connected with one end of the bell crank to be closed upon movement of the bell crank from one position to another position and provided with biasing means for opening the contacts upon response of the current-responsive holding means to release the prop from the other end of the fulcrum lever, a latch engageable with the other end of the bell crank for holding the crank in said other position and releasable upon the resulting movement of the bell crank upon release of the prop, and means biasing the fulcrum lever to return into engagement with the prop after the contacts are opened.
